UNITED STATES PATENT OFFICE.

CHARLES H. LANDENBERGER, OF PHILADELPHIA, PENNSYLVANIA.

DESIGN FOR WOVEN SKIRTING.

No. 38,826.

Specification for Design.

Patented Sept. 17, 1907.

Application filed August 9, 1907. Serial No. 387,933. Term of patent 3½ years.

To all whom it may concern:

Be it known that I, CHARLES H. LANDENBERGER, a citizen of the United States, residing in Philadelphia, Pennsylvania, have invented a new, original, and ornamental Design for Woven Skirting, of which the following is a specification.

The figure in the accompanying drawing is a face view of a piece of woven skirting showing my new design.

I claim:

The ornamental design for a woven skirting, as shown.

CHARLES H. LANDENBERGER.

Witnesses:

HAMILTON D. TURNER,
KATE A. BEADLE.
